UNITED STATES PATENT OFFICE

154,875

DESIGN FOR A BUILDING

Richard Pritchard, Milwaukee, Wis., assignor to Design Builders, Inc., Milwaukee, Wis., a corporation of Wisconsin

Application November 20, 1947, Serial No. 142,686

Term of patent 3½ years

(Cl. D13—1)

To all whom it may concern:

Be it known that I, Richard Pritchard, a citizen of the United States, residing in Milwaukee, in the county of Milwaukee and State of Wisconsin, have invented a new, original, and ornamental Design for a Building, of which the following is a specification, reference being had to the accompanying drawing, forming a part thereof.

The figure is a perspective view of a building, showing my new design.

I claim:

The ornamental design for a building, substantially as shown.

RICHARD PRITCHARD.
